[57] **CLAIM**

The ornamental design for a large knife handle, as shown and described.

DESCRIPTION

FIG. 1 is a front view of a large knife handle showing my new design, the rear view being a mirror image thereof;
FIG. 2 is a left side elevational view thereof;
FIG. 3 is a right side elevational view thereof;
FIG. 4 is a top plan view thereof; and,
FIG. 5 is a bottom plan view thereof.

The broken line showing of a knife blade in FIGS. 1-5 is for illustrative purposes only and forms no part of the claimed design.
